UNITED STATES PATENT OFFICE.

THEOPHILUS VAN KANNEL, OF NEW YORK, N. Y., ASSIGNOR TO VAN KANNEL REVOLVING DOOR COMPANY, OF NEW YORK, N. Y., A CORPORATION OF WEST VIRGINIA.

METALLIC FRAME FOR REVOLVING DOORS.

No. 813,602.

Specification of Letters Patent.

Patented Feb. 27, 1906.

Application filed July 22, 1905. Serial No. 270,768.

To all whom it may concern:

Be it known that I, THEOPHILUS VAN KANNEL, a citizen of the United States, residing at 524 East One Hundred and Thirty-fourth street, in the city, county, and State of New York, have invented certain new and useful Improvements in Metallic Frames for Revolving Doors, fully described and represented in the following specification and the accompanying drawings, forming a part of the same.

The present invention relates to the construction of revolving doors, which are often used in a segmental casing to afford ingress and egress for buildings without permitting the access of dust and drafts of air. The wings of such revolving doors are often made of wood, and in such case the rails and stiles are made solid and can be mortised strongly together, which gives the wings sufficient strength to resist torsion when connected with the center spindle by a rigid or hinged attachment; but when it is required to make the wings of metal a special difficulty arises in giving them the requisite stiffness, as it is undesirable to make the frame of solid bars on account of the great weight which would be involved. To secure lightness, metallic wing-frames have hitherto been made of rectangular sheet-metal tubing; but it has been found exceedingly difficult to impart sufficient strength to the joints of the rails and stiles to resist the lateral strain which results from pushing the wings around on the central pivot.

The object of the present invention is to furnish a construction for metallic wing-frames which shall not be unnecessarily heavy and which shall fit the frames to resist torsional or lateral strain. This object is attained by similar means both in respect to the two opposite wings, which are attached rigidly to the center spindle, and the two hinged wings, which are commonly jointed to the spindle so that they may be closed or swung parallel with the hinged wings when it is desired in mild weather to furnish a passage through the door-casing of the revolving door.

The means referred to consists of metallic arms, which in the case of the rigid wings are attached rigidly to the center spindle and project in opposite directions therefrom,

and in the case of the hinged wings consists of a metallic stile having the hinges jointed thereto and provided at the top with an integral arm to enter the upper tubular rail of the door-wing. The wing-frames in both cases are suspended from the arms, which are of such rigid character as to hold the wing-frames firmly and prevent them positively from bending. The joints of the rails at the outer corners of the wing are preferably strengthened by tubular angle-pieces and the joints of the intermediate rails by tubular ties secured within the ends of the rails and within the breadth of the stile. By these devices the wings are so attached to the center spindle as to revolve truly within the casing and clear the floor, the ceiling, and the curved surfaces of the casing in the desired manner.

An embodiment of the invention is shown in the annexed drawings, in which—

Figure 1 is a plan of the center spindle and the arms for the frames of the rigid wings fixed thereto. Fig. 2 is an elevation of the center spindle with the wings which are fixed to the spindle, the wing-frame at the left of the spindle being shown in section. Fig. 3 is an elevation of the center spindle with the wings which are hinged thereto, the wing-frame at the left of the spindle being shown in section. Fig. 4 is an enlarged section of one of the wing-frame corners, showing a tubular angle-piece. Fig. 5 is an edge view of the corner in section on line 5 5 in Fig. 4. Fig. 6 shows the joint of one of the rails and stiles with a tubular reinforcing-tie, and Fig. 7 is an edge view of the same with the rail and tie in section on line 7 7 in Fig. 6. Fig. 8 is a plan of the spindle in section on line 8 8 in Fig. 2, with parts of the connected wing-frames. Fig. 9 is a section on line 9 9 in Fig. 8, showing the spindle and the arms attached thereto. Fig. 10 shows the hinged connection of the stiles to the center spindle, the wing-frame and its stile being shown in section. Fig. 11 is a section of the center spindle on line 11 11 in Fig. 10, with parts of the adjacent wing-frames. Fig. 12 is a horizontal section on line 12 12 in Fig. 2 of two of the wing-frames and parts of the other frames and the center spindle, and Fig. 13 is an elevation of the center spindle with the parts in section at the center line where hatched.

Fig. 14 shows the spindle alone. Fig. 15 shows the spindle incased looking toward the ends of the arms H, and Fig. 16 is a similar view taken at right angles to the view of Fig. 15.

A designates the spindle, which in Fig. 2 is shown with a screw-thread upon the top to suspend it from a journal-bearing in the usual manner. A bolt B is shown fitted movably within the lower part of the spindle, so as to be withdrawn from the center step of the door when it is desired to move the wings bodily sidewise to clear the passage through the door-casing. In Fig. 2, C designates the tubular stiles of the wing-frames, which are fixed rigidly to the spindle by the means described.

D designates the end rails, which are jointed to the stiles by tubular angle-pieces E, (shown in Fig. 4,) and F designates the intermediate rail, jointed to the stile by a tubular tie-piece G. (Shown in Fig. 6.) Glass plates S are shown fitted in the wings above the rails F, and ornamental panels T are shown below the rails F, the glass being necessary to permit unrestricted observation through the wings of a revolving door. To support these wings, metallic arms H are notched into the spindle at opposite sides and clamped together upon the spindle by bolts P, (shown in Fig. 8,) which, with the notches Q, (shown in Fig. 9,) hold the arms rigidly at right angles to the spindle. The arms project from the spindle in opposite directions into the tubular rails D, the lower side of each arm being beveled to diminish its weight, while the upper side fits closely within the rails to sustain the weight of the wing. Each of such arms intersects the nearer stile, and therefore weakens the same, and to reinforce the joint and fully restore the strength of such stile each of such arms is provided with an integral elbow I, which extends within such stile and is secured therein by rivets or solder and serves to hold the stiles and rails square with one another. Similar opposite arms are shown attached to the spindle and extended into the intermediate rails F and are shown provided with elbows I, extending upwardly and downwardly, so as to strengthen the stile at such point and hold the joint square.

The angle-pieces E and tie-pieces G are shown of tubular cross-section in Figs. 4 to 7, inclusive, which affords both strength and lightness to the construction, and they may be secured in the joints by rivets or by sweating solder between the contiguous surfaces.

Referring to Figs. 3, 10, and 11, the outer stiles C of the hinged wings are shown jointed to the rails D and F in the same manner as the rigid wings; but the arm K, which supports the tubular wing-frame, is formed integral with a metallic stile J, which is provided with hinge-lugs N to engage lugs M upon the center spindle. Reinforcing-bars L are

shown riveted into holes or mortises through the metallic stile J at suitable points to fit within the bottom rail D and intermediate rail F, and thus stiffen them and hold them against lateral pressure. These reinforcing-bars are made, like the arms H and K, to fit snugly between the sides of the tubular rails, so as to resist lateral pressure and to sustain the torsion and prevent distortion of the wings when pressed sidewise by those who use the revolving door. The insertion of the angle-pieces E and tie-pieces G also serves to stiffen the door from lateral pressure, as well as the extension of the elbows I into the stiles adjacent to the arms H, as all of these devices contribute to stiffen the wings, and thus fit them to resist flexure under the lateral pressure to which they are subjected in use. The junction of these stiffening devices with the center spindle requires some special constructive features, as neither the spindle nor the solid stile J can be readily formed integral with the hinge-lugs which support the hinged wings. The hinge-lugs N for the wings are therefore formed upon a foot-plate O, which is secured to the edge of the stile J by rivets or by screws R, as shown in Figs. 10 and 11. The hinge-lugs of the spindle are formed as collars M, which are preferably connected by an integral sleeve U, which holds them separated at a suitable distance to admit the lugs N between the collars. The sleeve and lugs are readily attached to the spindle by set-screws, (indicated at W' in Fig. 11.) A pintle V is shown connecting the hinge-lugs in Fig. 10, and the hinge connection of the wings to the spindle is thus made strong and secure. A special construction is also required where the arms H are attached to the spindle, as the spindle is commonly made hollow to receive the step-bolt B and the rod Y, which actuates the usual locking-plate at the top of the spindle. The notches Q, which receive the inner ends of the arms H, (see Figs. 8 and 9,) therefore materially weaken the spindle, and to reinforce the same a tubular plug X is driven tightly within the bore of the spindle to stiffen it between the notches, the central hole of the plug admitting the rod Y, which is extended to the top of the spindle to operate the locking-plate.

Fig. 2 shows the carriage 25, which is commonly used to sustain the principal weight of the revolving door and made movable laterally on supporting-wheels 26 to clear the passage-way of the revolving-door casing when the doors are folded.

Figs. 12 and 13 show the sliding handle Z projected through a slot 1 in the side of the spindle to operate the step-bolt B and the rod Y. This handle is attached to a sliding collar 2, fitted to the outside of the spindle adjacent to the slot 1 and has a stud 3 projected into the upper end of a link 4, which is connected at the lower end by a swivel or rota-

table connection 5 with the upper end of the step-bolt B. The top of the link 4 is formed with a cup or recess 6, in which the lower end of the rod Y rests, so that when the handle Z is lifted to draw the step-bolt from its step in the floor it operates simultaneously to raise the rod Y and detach the locking-plate at the upper end of the spindle, so that the spindle when the wings are folded is capable of moving laterally within the casing to clear the passage-way. The locking-plate 7 is shown in Fig. 2 with one end hinged to the carriage and lug 27 at the other end to engage a notch in one of the supporting-beams when the spindle is set in its step. It is evident that the lifting of the locking-plate by the rod Y would disengage the lug 27 and permit the carriage and spindle to be shifted.

The construction of the carriage and locking-plate are shown in my Patent No. 641,563, dated January 16, 1900, for improvements in revolving-door structures, and the rails or beams for supporting the carriage are not shown herein, as their construction is already well understood.

In Figs. 8, 11, 12, and 13 a box or casing is shown applied to inclose the whole length of the center spindle at the outer line of the hinge-lug collars M, the box consisting of box-plates 18, screwed to the edges of the collars and secured upon the opposite sides of the collars, but leaving a vertical opening above the same which is closed by a detachable plate 20, which, with plates 24 on the hinged doors, serve as moldings to ornament the joints. In Fig. 12 the link 4 is shown where it is intersected by the lifting-pin 3, and also the sliding collar 2 with the handle Z projected outward through the box-plate 18, through a slot marked 21 in Fig. 16. To sustain the step-bolt when lifted by the handle Z, a latch-piece 15 is hinged to the lower side of the handle and formed with a shoulder 16 to engage the bottom of the slot 21, the pivot of the latch-piece being set forwardly enough to make the shoulder 16 swing forward automatically by its gravity into engagement with the bottom of the slot when the handle is raised. When it is desired to lower the step-bolt, the latch is readily pushed inward with the finger and disengaged from the plate 18. To prevent the step-bolt from wearing in its step as the door is rotated, the step 8 is formed with a cross-pin 9 and the end of the step-bolt with a slot 10 to engage such pin to hold the step-bolt from rotation, and the swivel connection 5 is provided to permit the rotation of the handle Z with the center spindle when the door is revolved upon the stationary step-bolt. To facilitate the renewal of the step 8 and to prevent the wear of the same by pedestrians in a season when the revolving door is not in use, I fit the step removably to a permanent socket 11, which is shown secured in the floor 12 by a

lead setting 13, the floor being commonly made of stone. The step is shown formed with a flange secured in the top of the socket by screws 14, and can thus be detached when not needed as a step and renewed if worn or injured.

It will be observed that the spindle is a straight tube, which permits the sleeves carrying the hinge-collars, and the collar 2, which carries the handle 3, to be readily fitted and adjusted at the required point upon the spindle. The pin 3 is screwed at its outer end within the handle, so as to be removable from the top of the link 4, and can thus be inserted in the top of the link when the latter is set in position with the bolt within the spindle. The rod then rests in the cup 6 of the link, to be operated by its movement for lifting the locking-plate.

It will be understood that in a metallic wing-frame the metallic panels between the rail F and the bottom rail D can be readily made so rigid as to prevent the wing-frame from sagging, and the arms H and K are not, therefore, fitted closely to the bottoms of the rails, but are fitted closely to the sides of the rails, so as to resist all lateral movement and wholly support the torsion which is imposed upon the wings when turning the revolving structure.

The means provided for jointing the butt-ends of the arms H to the spindle suffice in practice to hold those arms rigid and to prevent any injurious flexure of the two rigid doors.

The arms L are not shown fitted tightly to the tops or bottoms of the rails, but are fitted tightly to their sides, so as to hold the flat sides of the rails from bending. Such arms, as well as the arms K, formed integral with the stiles J of the hinge-doors, serve as a carrier for the wing-frames and hold all of the rails of each wing firmly in the same plane.

Metallic moldings 22 are shown in Fig. 12 to secure the glass plates S in the wings, and the usual hand-rail 23 is shown in Fig. 12 extended across one of the wings.

Strips 24 are shown upon the wing-frames adjacent to the hinge-lugs N to contact with the box-plates 18 and 19 when the hinged doors are set in an operative position, as is shown in Figs. 8, 11, and 12.

Having thus set forth the nature of the invention, what is claimed herein is—

1. In a revolving door, the combination, with the center spindle, of metallic arms attached rigidly to the spindle and projected in opposite directions from the spindle, and two opposite wing-frames mounted upon the said arms.

2. In a revolving door, the combination, with the center spindle, of arms having their butt-ends fitted respectively to opposite sides of the spindle and clamped together upon the spindle, the arms projecting in opposite di-

- rections from the spindle and having opposite wing-frames mounted thereon.
3. In a revolving door, the combination, with the center spindle, of arms having their butt-ends notched into the said spindle at opposite sides and clamped together upon the said spindle, the arms projecting in opposite directions from the spindle and having opposite wing-frames mounted thereon.
- 10 4. In a revolving door, the combination, with a center spindle and opposite wing-frames having tubular rails, of metallic arms attached rigidly to the spindle and projected in opposite directions from the spindle and fitted within the said rails.
- 15 5. In a revolving door, the combination, with the center spindle and opposite wing-frames having tubular rails, of metallic arms attached rigidly to the spindle and projected in opposite directions from the spindle into the said rails, the arms being tapered upwardly upon the under side to lighten them, substantially as herein set forth.
- 20 6. In a revolving door, the combination, with a center spindle and opposite wing-frames having tubular stiles and rails, of metallic arms attached rigidly to the spindle and projected in opposite directions from the spindle and fitted within the said rails and having
- 25 30 7. In a revolving door having metallic wing-frames, the combination, with the center spindle, of a wing-frame carrier consisting of a metallic stile having an upper arm projected rigidly therefrom and extended within the upper rail of the door-frame, and means for mounting the said carrier upon the spindle.
- 35 40 8. In a revolving door having metallic wing-frames, the combination, with the center spindle and hinge-lugs thereon, of a wing-frame carrier consisting of a metallic stile hinged to the said lugs, and having an upper arm projected rigidly therefrom and extended within the upper rail of the wing-frame.
- 45 50 9. In a revolving door having metallic paneled tubular wing-frames, the combination, with the center spindle and hinge-lugs thereon, of a wing-frame carrier consisting of a metallic stile hinged to the said lugs and having a rigid upper arm projected within the upper rail of the wing-frame, and auxiliary arms projected into the lower panel-rails of the frame.
- 55 60 10. In a revolving door, the combination, with a metallic paneled wing-frame formed of metallic tubes, of a wing-frame carrier comprising a metallic stile with rigid upper arm extended into the upper rail of the wing-frame, and auxiliary arms extended into the lower rails of the wing-frame, such auxiliary arms being mortised into the metallic stile and secured rigidly therein.
- 65 11. In a revolving door, a carrier for tubular metallic wing-frames comprising the me-
- tallic stile J having the upper integral arm K fitted snugly within the frame, and lower arms composed each of a plurality of bars mortised into the stile and secured rigidly therein, to fit within the lower rails and resist lateral flexure.
12. In a revolving door having tubular metallic wing-frames, the combination, with the joints of the rails and stiles, of tubular ties secured firmly within the ends of the rails and within the breadth of the stile, substantially as herein set forth.
13. In a revolving door, the combination, with the center spindle having a hinge-sleeve with a plurality of hinge-lugs thereon, of a tubular wing-frame, and a frame-carrier having a metallic stile with arms extended into the rails of the wing-frame, and hinge-plates secured rigidly to the said stile and having hinge-lugs to engage the hinge-lugs upon the center spindle.
14. In a revolving door, the combination, with the center spindle, of the means for hinging the wing-frame thereon, consisting of the sleeve U provided with the series of collars M formed at opposite sides with hinge-lugs, and hinge-lugs N upon the door-frame adapted to engage the same.
15. In a revolving door, the combination, with a tubular center spindle and door-wings having hinge-lugs near the top and bottom, of hinge-sleeves bored to fit upon the spindle and having collars with hinge-lugs to engage the lugs upon the wings, and means for securing the hinge-sleeves upon the spindle at suitable points.
16. In a revolving door, the combination, with a tubular center spindle with door-wings carried thereby and having the slot 1 as set forth, of the handle Z with sleeve 2 fitted to slide on the spindle over the slot, the link 4 having connection to the handle through the slot, and the step-bolt B having swivel connection with the link, whereby the step-bolt may be reciprocated in the spindle, and the spindle rotated without turning the step-bolt.
17. In a revolving door having a center spindle with wings hinged thereto, the combination, with a tubular center spindle having the slot 1 as set forth, of hinge-sleeves U secured thereon at intervals and having the hinge-lug collars M, the plates 18 and 19 forming a box around such collars and having the slot 21 in line with the slot 1 upon the spindle, the handle Z extended through the slot 21 and having the sleeve 2 fitted to slide on the spindle, the link 4 movable within the spindle, the pin 3 connecting the handle with the link, the step-bolt B movable with the link, and the rod Y extended from the top of the link to actuate the locking-plate at the head of the spindle.
18. In a revolving door having a center spindle with wings carried thereby, the com-

5 bination, with a tubular spindle having notches Q in its opposite sides, of arms having their butt-ends fitted to the said notches and projected in opposite directions to stiffen the wing-frames, bolts clamping the arms together upon the spindle, and the reinforcing-plug X fitted to the bore of the spindle between the notches to stiffen the same.

19. In a revolving door having tubular 10 spindle with wings carried thereby, the combination, with the spindle having slot 1 as set forth, of a link within the spindle and a handle connected with the same through the slot 1,

the bolt B having swivel connection with the link and provided in the end with the notch 15 10, and a step fitted to the step-bolt and having transverse pin 9 to engage the notch 10, whereby the bolt may remain stationary when the spindle and wings are revolved.

In testimony whereof I have hereunto set 20 my hand in the presence of two subscribing witnesses.

THEOPHILUS VAN KANNEL.
